Samuel W. Gibbs, of Albany, N. Y.

Assignor to Rathbone & Co.

Letters Patent No. 1212, dated Mar. 20, 1860.

The schedule referred to in these Letters Patent and making part of the same or all whom it may concern:

Be it known that I, Samuel W. Gibbs, of the City of Albany in the County of Albany, and State of New York, have invented or produced a new and original design for the plates of a square Oven Cook Stove, and I do hereby declare that the following is a full and exact description thereof, reference being had to the accompanying drawings and to the letters of reference marked thereon.

Fig: 1. represents the back of said Cook Stove with ornamental bead A, running along the top and bottom and vertically nearly the height of said back & forming the three panels as shown, with the ornaments B, forming the center and ornamental portion of the said Back plate.

Fig: 2. represent the Oven Doors of the said Stove constructed of the ordinary panel molding and forming in combination a panel of which the ornaments C and D. form the ornamental portion of the said Oven Doors.

Fig: 3. represents the lower front of the said Stove, panelled by the molding E, of which the ornaments F & G. are the ornamental center of the said panel, forming in combination the ornamental lower front of said Stove.

Fig: 4. represents the upper front plate of said Cook Stove with the front Doors in their proper place, the ornaments H. and I. forming the ornamental centers of said Doors, the whole forming in combination the ornamental plates of a square Oven Cook Stove.

What I claim as my invention and desire to secure by letters patent is the ornamental configuration of the plates of a square Oven Cook Stove as herein described and set forth.

Witnesses,

Henry W. Gibbs,
W. J. Kelly.
